DESIGN FOR A BOX FOR A BOTTLE OR SIMILAR ARTICLE

Georges Baud, Paris, France

Application August 21, 1946, Serial No. 132,707

Term of patent 3½ years

(Cl. D58—12)

To all whom it may concern:

Be it known that I, Georges Baud, a citizen of the Republic of France, residing at Paris, France, have invented a new, original, and ornamental Design for a Box for a Bottle or Similar Article, of which the following is a specification, reference being had to the accompanying drawing, forming part thereof, in which the figure is a perspective view of a box employing my new design.

The bottom and sides of the box not visible in the drawing have substantially the same surface embellishment as the portions shown.

I claim:

The ornamental design for a box for a bottle or similar article, substantially as shown and described.

GEORGES BAUD,
